UNITED STATES PATENT OFFICE.

NICHOLAS R. GUILBERT, JR., OF MELROSE PARK, PENNSYLVANIA, ASSIGNOR TO
ELEVATOR SAFETY-APPLIANCE CO., A CORPORATION OF PENNSYLVANIA.

DOOR.

Application filed February 5, 1925. Serial No. 6,941.

My invention relates to doors and more especially to that class of sectional doors commonly employed in warehouses, freight sheds, steamship docks, factories and other 5 similar locations where large doorway openings are required.

Among the principal objects of my invention are to provide a door comprising a plurality of relatively movable sections 10 adapted to fully close the door opening when in closed position and which when being moved from closed to open position and vice versa requires a minimum of space and that so located as not to materially detract from 15 the storage capacity of the building with which the door is associated. A further object of the invention is to provide a door of the character aforesaid which, when in open position, is disposed adjacent the under side 20 of the lintel of the doorway in a substantially horizontal position so as to leave the door opening entirely clear for its entire width and for substantially its entire height and consequently presenting no obstruction 25 to the movement of goods, trucks or the like through the doorway.

A still further object of the invention is to provide a door so constructed and operative 30 as to permit the piling or storage of goods and the like adjacent the inner side of the door when in closed position for a considerable height above the floor without interfering with the opening and closing of the door, thus enhancing the storage capacity of the 35 building by permitting the entire area of its floor to be used for storage purposes.

My invention further contemplates the provision of a sectional door and means for opening and closing the same which are of 40 relatively simple construction, not liable to get out of order or to jam under conditions of use and which may be manufactured and installed at a relatively low cost, as well as the general improvement and simplification 45 of doors and their attendant operating mechanism of the class to which my invention relates.

In addition to the foregoing objects my 50 invention further includes other objects and novel features of design, construction and arrangement hereinafter more particularly specified or which will be apparent from the accompanying drawings illustrating certain embodiments of the invention.

55 In the said drawings, which are of more

or less diagrammatic nature, Fig. 1 is a rear elevation of one form of door constructed in accordance with my invention and Fig. 2 is a top plan view thereof, a portion of the door frame being shown in horizontal section; Fig. 3 is an enlarged fragmentary view, partially in section and partially in elevation, illustrating a detail of the device and Fig. 4 a top plan view thereof partially in horizontal section. Fig. 5 is a section on line 5—5 in Fig. 1 looking in the direction of the arrows and showing the door in partially opened position and Fig. 6 a similar view showing the door in fully opened position, the door proper being shown in end elevation for the sake of clearness. Fig. 7 is a view similar to Fig. 1 but showing a somewhat modified form of the invention and Fig. 8 is a top plan view thereof corresponding to Fig. 2. In Figs. 9 to 11 inclusive I have shown a still further modified form of the invention, Fig. 9 being a fragmentary view of the door in rear elevation, Fig. 10 a section on line 10—10 in Fig. 9 looking in the direction of the arrows and showing the door in fully open position and Fig. 11 a fragmentary detail view in end elevation of a portion of the operating mechanism and also showing a part of the door frame in vertical section. The same symbols 85 are used to designate the same parts in the several figures.

Referring now more particularly to the form of the invention shown in Figs. 1 to 7 inclusive, the same comprises a door, generally designated as D, having an upper section 1 and a lower section 2 hingedly connected for relative movement by hinges 3—3 so designed as to permit the two sections to fold together along a horizontal axis with 90 their rear or inner faces adjacent and in substantially parallel relation. Disposed to extend vertically adjacent each of the jambs or sides of the doorway formed in and framed or defined by the wall W of the 100 building is a preferably metallic guide 4, best shown in Fig. 4, conveniently of channel section and provided with a centrally disposed vertically extending rib 4'. Each guide is securely fastened to the rear face of 105 the adjacent door jamb with its open side extending toward the doorway and the door which is of sufficient width to almost fill the space between the guides is disposed in alignment or substantial alignment there- 110

with so that when in closed position the door will lie in a plane somewhat in the rear of the plane of the inner face of the frame of the doorway.

6 Arranged for cooperation with the upper section of the door and with each guide is a slide 5 of suitable design, one form of which, best shown in Figs. 3 and 4, comprises a pair of spaced fingers 5' operative to receive the rib 4' between them as well as a suitable ear 6 for the attachment of one of the lifting chains as hereinafter more particularly described; each slide is suitably pivotally connected with the door section, 10 conveniently by means of an L-shaped plate 7 which is fitted over the edge of the door and carries a horizontally disposed pivot stud 8 having a head countersunk in a depression 9 in the edge of the door and a trunnion projecting laterally outward and received in a cylindrical hole of suitable diameter formed in the adjacent portion of the slide, the arrangement being such that the door section 1 can freely rotate in the vertical plane upon the pivots thus formed, whose axes are in horizontal alignment, whatever may be the position of the slides with respect to the guides.

30 The lower door section 2 is also in like manner pivotally connected to slides 10, which may be similar in design to slides 5, adapted to engage the vertically extending rib 4' in the guides 4, and I prefer to arrange the pivotal connection between this section 35 of the door and its slides as near to its lower edge as may be convenient but in any case, in order that when the door is in fully open position the two sections thereof may lie in substantially parallel relation as herein-after more fully described, it is requisite that the distance between the pivotal center of the hinges 3 and the axis of the pivots 8 or other pivotal connection between the upper section of the door and its slides shall be 40 substantially the same as the distance between the said pivotal center and the axis of the pivots between the lower section of the door and its slides.

45 In the embodiment of the invention now being described suitable means are provided for constraining the upper extremity of the door section 1 to move in a given path during the opening and closing of the door, a convenient form thereof comprising a pair 50 of tracks or rails 12 respectively disposed adjacent the sides of the door and supported in any suitable way such, for example, as by hangers 13 depending from the ceiling or roof of the building. These rails may be 55 arranged to extend rearwardly from the inner face of the building wall for a distance slightly greater than the distance between the upper door section pivots and the upper edge of the door and a suitable slide 60 65 14 is arranged on each side of the door sec-

tion adjacent its upper side in such manner as to engage the adjacent track and slide thereon as the door is opened and closed. It is requisite therefore that these slides be pivotally connected to the door section so as to be capable of rotation about a horizontal axis with respect thereto when the door is being moved and such connection may be conveniently effected through the medium of an L-shaped plate 15 substantially corresponding to plate 7 already described and having a cylindrical aperture for the reception of a pivot stud 16 carried by the slide. While the tracks or rails as well as the slides may be of any suitable 75 form, the former may conveniently be of L-shaped cross section and disposed so that their flanges will lie respectively in horizontal and vertical planes, and the slides, under such conditions, substantially jaw-shaped 80 so as to engage over a portion of the adjacent horizontal flange, but any other desired arrangement may be employed with equal facility. Furthermore, in order that the door when fully open may assume a substantially horizontal position as close to the top of the door opening as possible, it is desirable to slightly downwardly incline the tracks when, as shown in Figs. 5 and 6, their forward ends are disposed at a point above 85 that in which the pivots of the upper section of the door come to rest when the door is fully opened for it will be obvious that to permit the door, when so opened, to assume the said position it is requisite that the pivots of the slides 14 and 5 shall be in a substantially horizontal plane, a condition which may be readily brought about by suitable inclination of the tracks as hitherto stated.

90 A sectional door constructed and supported substantially as hitherto described is capable of operation in accordance with my invention by various forms of mechanism such, for example, as that shown in Figs. 1 to 7 inclusive and now to be described, said mechanism being so designed and arranged as to substantially counterbalance the weight of the door and to simultaneously exert on both sections thereof a vertical lift 95 sufficient to move them simultaneously from substantially closed to fully open position. For accomplishing this result the said means may comprise a suitable counterweight 20 conveniently disposed at one side of and adjacent the upper part of the door when the latter is closed and connected, through the medium of a chain or cable 21, with the slide 5 carried by the upper section of the door on the opposite side thereof from that on which the counterweight is located, the chain being carried up from the slide through the adjacent guide, thence over one of a pair of independently rotatable, coaxially supported sheaves 22 secured to the 100 105 110 115 120 125 130

- wall above the door, thence horizontally to the opposite side of the door over one of a plurality of independently rotatable coaxially supported sheaves 23 secured to the 5 wall and thence to a point of connection 24 with the counterweight. In a similar manner the counterweight is connected with the slide 5 on the adjacent edge of the upper door section by a chain 25 passing upward 10 through the other guide and over another of the sheaves 23 and thence to the counterweight at 24.
- For supplying the requisite lifting force to open the door the lower section thereof 15 may be suitably connected to an operating winch X or the like, conveniently represented in Fig. 1, and located at any convenient point, said connection being effected by a pair of chains or cables 26 and 27 the 20 former of which extends from the ear 6' or other convenient point of attachment on the slide 10 on the opposite side of the door from the counterweight upwardly in the adjacent guide 4 and over another of the 25 sheaves 22, thence horizontally and over another of the sheaves 23 and thence vertically downwardly, conveniently through a suitable passage 28 formed in the counterweight, to a ring or shackle 29 situated below the weight; the other chain 27 is carried upward from the other slide 10, thence over another of the sheaves 23 and down through the same passage in the counterweight to the ring or shackle 29. From this ring a single 30 operating cable 30 may be extended to the winch so that a downward pull thereon is effective to move the shackle in a similar direction and thus impart a simultaneous pull upon both lifting chains. It will of 35 course be understood that while the winch or similar mechanism is a convenient one for supplying the requisite lifting force any other means suitable for that purpose may be employed or, under certain conditions, 40 the use of mechanical means for this purpose may be entirely dispensed with and the requisite force exerted manually on the free ends of the lifting chains 26 and 27.
- To open the door it is first requisite to 45 break the joint formed by the hinges 3 so as to move the sections of the door from the vertical plane and bring them to a slightly relatively inclined position, a result which may be accomplished either manually by 50 an outward push on the rear face of the door in the vicinity of the hinges or by any suitable mechanical means (not shown). The door sections having been thus caused to 55 assume a slightly angular relation with respect to each other, sufficient power is exerted on the free ends of the lifting chains 60 26 and 27 either manually or by means of the winch X to cause the slides 5 and 10 to move upwardly in the guides 4, the upper 65 part of the lower door section and the lower
- part of the upper door section simultaneously swinging outwardly and the upper end of the upper section moving along the tracks 12 until the sections reach a substantially horizontal position with the lower 70 section folded beneath the upper section as shown in Fig. 6, thus fully opening the door. As the counterweight is preferably designed so as to almost counterbalance the weight of the door, the amount of force required to be exerted on the lifting chains 75 to open the door is not very great and it may thus be desirable to maintain a certain tension on the free ends of the lifting chains to hold the door open; thus, upon release of 80 this tension the door, under ordinary conditions, is operative to automatically return to closed position through the action of gravity. It will be noted that during the opening of the door an upward lifting force 85 is exerted simultaneously on both sections thereof, the pull of the counterweight being delivered directly to the upper section of the door through the slides 5 and the manual or mechanical lifting force being delivered directly to the lower section through the slides 10, thus moving both sections simultaneously from their initial or closed to their final or open position in which they are supported 90 closely adjacent the top of the doorway and in a position entirely out of the way of loaded trucks or the like passing therethrough. It will moreover be observed that the only portion of the door which extends into the interior of the building at any time, either 95 during the opening and closing movements or when the door is at rest in fully open position, is that part of the upper section above the pivots 8, thus enabling goods to be piled close to the inner face of the closed 100 door at least as high as the said pivots without interfering with its opening or closing, a feature of material advantage in enhancing the capacity of the warehouse or other building with which the door is associated. 110
- In the form of invention just described but a single counterweight is utilized and the operating mechanism of the door so arranged that the force requisite for opening it may be exerted at a single point conveniently at one side of the door through the medium of a winch or other equivalent means. Under certain conditions, however, and particularly in installations where the doors are not large or particularly heavy it 115 may be desirable to dispense with the use of mechanical power and operate the door solely by a manual force applied directly to the door itself instead of a mechanical or manual force applied to the lifting chains. Under such conditions it may be desirable to employ a pair of counterweights 35, 36 disposed on opposite sides of the door as shown in Figs. 7 and 8 which may be respectively 120 directly connected with the slides 5 by 125

means of chains or cables 37 and 38 passing over sheaves 39 and 40 respectively supported above and adjacent the opposite edges of the door. When so arranged the combined weight of the counterweights is preferably such as to almost overbalance the weight of the door so that the operator by first pushing outwardly on the door in the vicinity of the hinges 3 so as to break the joint between the sections can thereafter by further outward and upward pressure on the lower part of the upper section or an upward pull on the lower part of the lower section cause both sections to move upwardly and toward each other until they reach a substantially horizontal position adjacent the top of the doorway, the upper edge of the upper section of the door moving along the tracks 12 during this opening movement through the coaction of the slides 14 with the tracks as hitherto described. Ordinarily the weight of the parts in this form of the invention will be so designed that the door will remain in open position automatically through the friction between the various relatively movable parts though capable of being readily returned to closed position by a downward pull sufficient to overcome such friction. Of course once the door is fully closed the pull exerted thereon by the counterweights is a vertical one and it cannot operate to open the door until the joint between the sections is broken in some suitable manner as already described, but as soon as the sections are moved to a slightly relatively inclined position the pull of the counterweight or counterweights becomes effective to assist in the actual opening of the door.

In the forms of the invention heretofore described means are provided for constraining the upper extremity of the upper section of the door to move in a given path, namely, that defined by the tracks 12, during the actuation of the door, but under certain conditions it may be desirable to avoid the employment of the tracks or equivalent means for guiding the upper edge of the door during the major part of its movement and I shall therefore now proceed to describe a form of the invention illustrated in Figs. 9 to 11 inclusive in which no means for guiding the upper edge of the door during the major portion of its travel are employed and which is intended, similarly to the form of the invention shown in Figs. 1 to 6, to be actuated by power supplied at a single point adjacent the door either mechanically by a winch X or manually.

In this form of the invention the slides 5 of the upper section 1 are respectively connected by chains or cables 50 and 51 with a single counterweight 52 conveniently disposed at one side of the door, the chain 50 being carried upwardly from the counter-

weight over one of a plurality of independently rotatable, coaxially supported sheaves 53, thence horizontally above the door and over one of a pair of coaxially supported, independently rotatable sheaves 54 and 70 thence downwardly through the adjacent guide 4 to a point of connection with the adjacent slide 5 while the other chain 51 is carried upwardly from the weight 52 over another of the sheaves 53 and thence downwardly through the adjacent guide to the other slide 5 so that the pull of the counterweight is exerted directly upon both sides of the upper door section. The slides 10 in this case, however, are not directly connected with the winch through the medium of the lifting chains as in the form of the invention first described, but, instead, the lifting chains 55 and 56 are respectively carried up from the slides 10, thence respectively over two other of the sheaves 53, thence downwardly over two independently rotatable sheaves 57 supported on a horizontal axis in a suitable housing 58 secured to the counterweight and thence upwardly to a dead end, 80 conveniently an eye-bolt 60 or the like supported from the wall W, while the lower end of the counterweight is connected by a chain or cable 61 with the winch X if employed, so that through the medium thereof a downward pull can be imparted to the weight. 85

In this form of the invention the door is opened, after the joint between the sections has been broken as already described, by imparting a sufficient downward pull on the counterweight to cause the slides 5 and 10 to travel upwardly along the guides, the upper edge of the lower section and the lower edge of the upper section swinging outwardly and the upper edge of the latter traveling rearwardly during the opening movement, but as, owing to the manner of connection of the lifting chains, the slides 10 are caused to move along the guides at twice the speed of the slides 5, it is requisite, to enable the door to assume a horizontal position when opened with its sections in substantial parallelism, that the distance between the center of the hinges 3 and the pivots of the slides 5 and 10 shall be the same and shall approximate substantially one-fourth of the total height of the door. It is furthermore desirable in order to afford a support for the upper edge of the door when opened and to insure its assuming a substantially horizontal position, to provide means for receiving and guiding said upper edge as the door is approaching the end of its opening movement, such means conveniently comprising a support 64 hung from the ceiling by hangers 66 or otherwise positioned and having its forward edge 64' forwardly and downwardly inclined, so that as the door is finishing its opening movement its said upper edge will engage the in- 125

clined surface 64' and slide upwardly thereon as the door finally comes to rest with its upper edge upon the horizontal surface of the support.

5 It is thought that the mode of operation of this particular form of the invention will be apparent without extended description, the weighting and proportioning of the parts being conveniently such that a slight 10 tension on the cable 61 is required to hold the door open so that the release of said tension is all that is necessary to permit the door to automatically close under the action of gravity.

15 While I have herein described with considerable particularity certain forms of my invention respectively adapted to meet the requirements of different conditions of installation, I do not thereby desire or intend 20 to specifically limit myself thereto or to any precise details of construction or arrangement of the details of the device or to the particular form and arrangement of operating means to which I have referred, as the 25 same may be modified in numerous ways to better adapt the invention to the particular purposes and operative conditions under which it is to be employed or for other reasons without departing from the spirit and 30 scope of the invention as defined in the appended claims.

Having thus described my invention, I claim and desire to protect by Letters Patent of the United States:—

35 1. The combination with a door frame defining a doorway, of a door for closing said doorway and comprising a pair of sections hinged together on a horizontal axis, guides supported adjacent the sides of the doorway, 40 slides cooperative with said guides and respectively pivotally connected to said section, means for causing the upper edge of the door to follow a substantially horizontal path during the opening and closing of the 45 door, and means for exerting an upward pull on said slides whereby said slides may be caused to move upwardly in said guides to carry said door sections from a substantially vertical to a substantially horizontal position 50 adjacent the top of the doorway, extending partially therethrough and disposed one above the other in substantially parallel relation.

55 2. The combination with a door frame defining a doorway, of a door comprising a pair of sections hinged together on a horizontal axis and adapted when vertically extended to close said doorway, vertical guides extending adjacent the sides of the doorway, 60 means for effecting pivotal connection between each of said sections and said guides, means for causing the upper edge of the door to follow a substantially horizontal path during the opening and closing of the 65 door, and means for simultaneously exert-

ing a lifting force on said sections whereby said sections, through coaction of said connecting means and said guides and said door and said second means, are simultaneously caused to swing outwardly through the door 70 and move from a substantially vertical to a substantially horizontal position while being raised to the top of said doorway to partially extend therethrough and rest in substantial parallelism one above the other. 75

3. The combination with a door frame defining a doorway, of a door comprising a pair of sections hinged together and relatively movable about a horizontal axis, a guide extending adjacent each side of the 80 doorway, a pivotal connection between each of said sections and each of said guides, said connections being disposed equidistantly from the adjacent edges of the sections, and means for simultaneously exerting a lifting 85 force on both of said sections.

4. The combination with a door frame defining a doorway, of a door comprising hingedly connected upper and lower sections, the latter being of less vertical height than the 90 former, adapted when extended in a vertical plane to close said doorway, a guide disposed adjacent each side of the doorway, a pair of horizontally aligned slides respectively cooperative with the guides and pivotally connected with the upper section, a pair of horizontally aligned slides respectively cooperative with said guides and pivotally connected with the lower section, 95 means for simultaneously exerting a lifting force on all of said slides and means for causing the upper edge of the upper section of the door to move in a straight substantially horizontally disposed line whereby 100 upon application of said force said sections 105 may be caused to move from a substantially vertically aligned position adjacent the doorway to a substantially parallel horizontal position adjacent the top of the doorway and 110 extending therethrough.

5. The combination with a door frame defining a doorway, of a door comprising hingedly connected upper and lower sections adapted when extended in a single plane to close the doorway, a vertically extending guide adjacent each side of the doorway, means pivotally supporting each section for rotation about an independent horizontal axis, said means being slidably cooperative 115 with said guides, means for simultaneously exerting a lifting force on all of said connecting means to cause said means to move longitudinally of said guides, and means for constraining the upper edge of the upper section to move in a given path during a portion of the movement of said supporting means. 120

6. The combination with a door frame defining a doorway, of a door adapted to close the doorway when in vertical position 125 130

and comprising a pair of sections of unequal height hinged together for relative movement on a horizontal axis, a vertically extending guide disposed adjacent each side of the doorway, a pair of slides cooperative with each guide disposed one above the other with respect thereto, the upper slides of each pair being pivotally connected with the upper door section in horizontal alignment with each other and the lower slide of each pair being similarly connected with the lower section, means adapted to constrain the upper edge of the upper section to move in a given path during a part of the opening movement of the door, and means for simultaneously applying a lifting force to each of said slides to cause said slides to move upwardly along the guides whereby the sections of the door are caused to swing about their respective pivotal connections with the slides and pass from a substantially vertical position adjacent but out of the plane of the doorway to a substantially horizontal position adjacent the top of the doorway and extending therethrough.

7. The combination with a door frame defining a doorway, of a sectional door comprising two sections of different vertical heights hingedly connected together and adapted when extended in a vertical plane to close the doorway, a vertically extending guide adjacent each side of the doorway, a pair of slides respectively cooperative with the guides and pivotally connected in horizontal alignment to opposite sides of the lower section, another pair of guides similarly connected to the upper section, said pairs of guides being respectively equidistant from the axis about which the sections are relatively movable, means for exerting a vertical lifting force simultaneously on all of said slides whereby said slides may be caused to move upwardly in said guides and approach each other and said sections moved relatively to each other about their point of connection and turned from a substantially vertical position to a substantially vertically and horizontally aligned position adjacent

the top of the doorway and means operative to cause the upper edge of the upper door section to move in a straight substantially horizontally disposed line during the relative movement of said sections.

8. In combination with a door frame defining a doorway, a door comprising sections hinged together, means for applying a lifting force to both sections simultaneously but separately and means for causing said sections under the influence of said force to simultaneously swing from a substantially vertical to a substantially horizontal position.

9. In combination with a door frame defining a doorway, a door comprising two sections of unequal height hinged together for relative movement on a horizontal axis, means for simultaneously yet separately applying a lifting force to both of said sections and means for causing said sections, under the influence of said force, to swing from a substantially vertical position in the rear of and closing said doorway to a substantially horizontal position adjacent the top of the doorway and extending therethrough.

10. In combination with a door frame defining a doorway, a two part sectional door, the sections thereof being hinged together for relative movement, means remote from the connection between the sections for guiding each section with respect to the door frame, means for exerting a lifting force on both sections simultaneously to cause said sections to move upwardly with respect to the frame while turning about said hinge connection from a substantially vertical to a substantially horizontal position with said sections folded one against the other in substantial parallelism and means operative to cause the upper edge of the upper door section to move in a straight substantially horizontally disposed line during the movement of said sections.

In witness whereof I have hereunto set my hand this 3rd day of February, 1925.
NICHOLAS R. GUILBERT, JR.
